UNITED STATES PATENT OFFICE.

DANIEL H. FOSTER, OF GOWANDA, NEW YORK.

UNIT STEAM OR HOT-WATER RADIATOR.

Application filed March 4, 1926. Serial No. 92,310.

This invention relates to unit steam or hot water radiators and more particularly to a steam or hot water radiator which embodies its own heating plant.

5 An important object of the invention is the construction of the combustion chamber so that a maximum heating surface is afforded.

10 A further object of the invention is to provide a construction whereby the combustion chamber may be conveniently vented without marring the appearance of the finished radiator.

15 A still further object of the invention is to provide an outlet vent for the radiator of such character that back draft, such as often occurs in a faulty chimney, is prevented from reaching the combustion chamber.

20 A further object of the invention is to provide a construction whereby these objects may be attained with but a slight modification of certain of the sections of the radiator.

25 These and other objects I attain by the construction shown in the accompanying drawings, wherein for the purpose of illustration is shown a preferred embodiment of my invention and wherein:—

Figure 1 is a rear elevation of a radiator constructed in accordance with my invention;

30 Figure 2 is a side elevation of an ordinary unit;

Figure 3 is a vertical sectional view through a vented unit;

Figure 4 is a section on the line 4—4 of Figure 3;

Figure 5 is a transverse sectional view through the lower end of one section of the radiator on the line 5—5 of Figure 4;

Figure 6 is a rear elevation of the vent header;

Figure 7 is an end elevation thereof;

Figure 8 is a view of a modified header;

Figure 9 is a top plan of the header cap, the pipe connection being indicated in dotted lines.

50 Referring now more particularly to the drawings, the radiator consists of a plurality of units including intermediate units subdivided into vent units 10 and ordinary units 11, and a pair of end units 12. Each ordinary unit 11 has at its upper and lower ends cored chambers 13 and 14, the chamber 14 at the lower end of the unit being subdivided by a transverse partition wall 15 to produce 55 a third or combustion section chamber 16. The chambers 13 and 14 are connected by

aligned vertical tubes 17. The chambers 13 and 14 each have in their side walls openings 18 surrounded by thimble seats 19, for the reception of the ends of thimbles 20 forming 60 the connections between adjacent units. The chamber 16 has in its opposite side walls openings 21 to permit the insertion of a burner 22 and to provide exit openings for the products of combustion. The bottom 65 wall of the chamber 16 is provided with an opening 23 for the entrance of air and of which the openings 21 are extensions. Each section has on opposite side faces thereof an inverted U-shaped rib 24, comprising an intermediate portion 25 which is arranged at a point intermediate the ends of the tubes or columns 17 and spaced downwardly extending side portions or legs 25' which extend approximately to the bottom of the section at opposite sides of the opening 21. The ribs at opposite sides of the section merge 70 with each other through the interstices 26 between adjacent columns 17.

75 In the assembled radiator, adjacent edges of the ribs 24 come into contact with one another and since the space between the sections below these ribs is in communication with the combustion chamber 16 through the openings 21, it follows that the products of 80 combustion from the burner 22 will pass upwardly between adjacent faces of the radiator sections and are permitted to pass about the lower ends of the columns 17.

85 Each vented section 10 is identical with the section hereinbefore described with the exception of the fact that, one of the tubes, connected with 17^a, has each end closed by partition walls 27 and 28. Adjacent its lower end, this tube is cut away at its inner side, as 90 at opening 29, so that the interior of the chamber 30 formed by the tube is in communication with the upper end of the combustion chamber, as defined by the ribs 24. The outer face of the tubes 17^a is provided 95 with outlets 31 and 32 at the upper and lower ends of the chamber 30. The end sections 12 are identical with the sections 11 with the exception of the fact that the outer faces thereof are made plain and free from the ribs 24 and the openings below the intermediate portion of the ribs 24 at the inner faces are filled by a web cast integral with the tubes 17. Thus, these sections serve to seal the 100 ends of the combustion chamber. The sections 10, 11 and 12 are held in assembled relation by the usual bolts 33.

In small radiators, where only a few sections are employed, but two of the vented sections 10 are used and these are generally placed at the center of the completed radiator. The upper openings 31 are connected by a vent cap 34, the cover of which, indicated at 35, is adapted for engagement with a flue pipe 36. In longer radiators, such as are at present illustrated, two of the vented sections 10 are employed at the center of the radiator and a single vented section adjacent each end of the radiator. A vent cap 37 is employed which is similar to the vent cap 34 with the exception of the fact that it has 15 openings 38 in its end walls. These openings are connected with the vent openings of the sections 10 adjacent the ends of the radiators by suitable manifolds 39.

It is pointed out that with the construction hereinbefore set forth, not only is an efficient heating of the fluid contents of the radiator obtained, but back draft to the combustion chamber is also effectually prevented. Any down draft which may enter through 25 the openings 31, in passing through the elongated chamber 30 will, in preference to changing its direction and bucking the heated gases rising through the opening 29, pass out through the opening 32 to the room. It is 30 also pointed out that those tubes used as stacks in the sections 10 act with the remaining tubes to supply heat to the room due to the fact that they are heated from the gases arising from the combustion chamber.

35 It will be obvious that the construction hereinbefore set forth is capable of a certain range of change and modification without materially departing from the spirit of the invention and I accordingly do not limit 40 myself to such specific structure except as hereinafter claimed.

I claim:

1. A radiator of the character described, comprising a plurality of upright units arranged in side by side relation and each comprising a plurality of tubes, said units having upper and lower lateral outlets whereby communication is established between the upper and lower ends of the tubes thereof, a 45 combustion chamber formed in the lower end of each unit and in communication through a lateral opening with the chamber of the adjacent unit, a burner extending longitudinally of the radiator through said chambers, 50 coacting elements positioned between the units to provide a heat chamber lengthwise of the radiator, and partitions across the upper and lower ends respectively of a tube of certain of the units, said last named tubes 55 being in communication with said heat chamber to receive products of combustion therefrom and having an outlet at the upper end thereof for the discharge of said products.

2. A radiator of the character described, 60 comprising a plurality of upright units ar-

ranged in side by side relation and each comprising a plurality of tubes, said units having upper and lower lateral outlets whereby communication is established between the upper and lower ends of the tubes thereof, a 70 combustion chamber formed in the lower end of each unit and in communication through a lateral opening with the chamber of the adjacent unit, said communicating chambers forming an elongated chamber longitudinally of the radiator, a burner extending through said longitudinal chamber, means to provide a heat chamber lengthwise of the radiator and communicating with the longitudinal chamber, partitions closing the upper 80 and lower ends of a tube of certain of the units, said last named tubes being in communication with said heat chamber to receive products of combustion therefrom and having outlet ports at the upper ends thereof 85 for the discharge of said products, and said tubes each further having a port adjacent the lower end lying in a plane lower than the point of communication of the tube with the heat chamber.

3. A radiator of the character described, comprising a plurality of upright units each embodying a plurality of tubes opening at their upper and lower ends into chambers, the upper and lower chambers of the units being in communication, a horizontal wall dividing the lower chamber of each unit to form a lower combustion chamber, open at its bottom and in lateral communication with an adjacent combustion chamber, a burner extending longitudinally of the radiator through said combustion chambers, coacting ribs interposed between the units and forming a longitudinally extending chamber above said lower chambers, and in communication with the combustion chambers, partitions closing the upper and lower ends respectively of a tube of a unit, said tube being open to the atmosphere at the upper and lower ends and further being in communication intermediate its ends with said heating chamber.

4. A radiator of the character described, comprising a plurality of upright units each embodying a plurality of tubes opening at their upper and lower ends into chambers, the upper and lower chambers of the units being in communication, a horizontal wall dividing the lower chamber of each unit to form a lower combustion chamber, open at its bottom and in lateral communication with an adjacent combustion chamber, an inverted substantially U shaped rib formed on the opposed faces of the units and comprising a transverse intermediate portion and spaced depending side portions, certain of the units having a rib on each face and having the intermediate portions of these ribs connected between the tubes thereof, the depending portions of the ribs extending downwardly to a point adjacent the lower ends of the support.

ing unit and disposed at opposite sides of a lateral communicating opening of the unit combustion chamber, the ribs of the units co-acting to form a continuous heat chamber longitudinally of the radiator, a burner extending longitudinally of the radiator through said combustion chambers, and partitions closing the upper and lower ends respectively of a tube of the unit, said tube being open to the atmosphere at each end and further being in communication intermediate its ends with said heating chamber.

5. A vent unit for a gas fired radiator, including a plurality of units, said vent unit comprising a plurality of tubes opening into a common chamber at each end of the same, the chamber at each end having a lateral open-

ing for communication with adjacent radiator units, a horizontal partition in one chamber below the lateral openings thereof forming a lower combustion chamber, said combustion chamber being open at the bottom and sides, partitions closing the ends of one of said tubes, said last tube having ports opening therefrom one adjacent each end and one intermediate the ends, and means whereby, when the unit is set up in association with the other radiator units, communication will be established between the combustion chamber and said closed tube through said intermediate port.

10 15 20 25 30
In testimony whereof I hereunto affix my signature.

DANIEL H. FOSTER.
